HANGER FOR SHOES OR THE LIKE

Roleigh Lee Stubbs, P.O. Box 383,
Jacksonville, Fla. 32201

Filed Feb. 28, 1966, Ser. No. 1,216

Term of patent 3½ years

(Cl. D80—8)

Fig. 1.

Fig. 2.

Fig. 3.

I claim:

The ornamental design for a hanger for shoes or the like, as shown and described.
